UNITED STATES PATENT OFFICE.

JOHN W. JONES, OF HADDONFIELD, NEW JERSEY.

SASH-HOLDING DEVICE.

1,373,964.

Specification of Letters Patent.

Patented Apr. 5, 1921.

Application filed September 19, 1919. Serial No. 324,911.

To all whom it may concern:

Be it known that I, JOHN W. JONES, a citizen of the United States, residing at Haddonfield, in the county of Camden and 5 State of New Jersey, have invented new and useful Improvements in Sash-Holding Devices, of which the following is a specification.

The invention relates to window sashes 10 and has for an object to provide a structure for a window frame and the sash, doing away with the usual sash weights and permitting of raising or lowering the sash relative to the frame and holding the sash in 15 any desired position relative to the frame.

The invention comprehends among other features a device which may be more aptly termed a weightless window sash and whereby the usual sash weights and cords 20 or chains for holding the latter, are dispensed with, suitable anti-friction balls being employed to facilitate the sliding operation of the sash relative to the frame and for holding the sash in any desired position.

25 In the further disclosure of the invention reference is to be had to the accompanying drawings constituting a part of this specification, in which similar characters of reference denote corresponding parts in all the 30 views, and in which,—

Figure 1— is a fragmentary elevation of a window sash and frame with parts broken away to disclose the underlying structure.

Fig. 2— is a fragmentary enlarged vertical sectional view of the structure shown in 35 Fig. 1, and

Fig. 3— is a fragmentary horizontal sectional view taken substantially on the line 3—3 in Fig. 2.

40 Referring more particularly to the views, the numeral 10 indicates a sash and the numeral 11, the window frame thereof, 12 indicating the usual parting strip between the upper sash 13 and the lower sash 10, with 45 the numeral 14 designating the front and back beading strips. It will of course be understood that the upper sash and frame construction and lower sash and frame construction are alike and therefore I will only 50 describe one application of my device to one of the sashes, namely the lower sash. In the window frame 11, I preferably secure a vertical housing 15, disposed to lie in the groove 16 formed by the parting strip 12 and beading strip 14, the housing being suitably secured to the window frame by suitable

55 screws 17. The housing consists substantially of a rear plate 18 and a front plate 19 with expansible helical springs 20 interposed between the plates as shown, the front 60 plate 19 being held in spaced relation with the rear plate 18 by the springs and prevented from extending too far forwardly by a stop flange 21 formed on the ends of the front plate and extended beneath another 65 flange 22 on each end of a forwardly extending portion 23 of the rear plate 18.

70 Suitably riveted or otherwise secured to the front plate 19 is a holding or supporting plate 24 which constitutes a part of the housing and is formed with a series of cupped portions 25 in which anti-friction balls 26 are loosely disposed with one of the balls 75 namely the one indicated by the numeral 27, slightly larger than the others, which latter acts to support the ball 27 in position so that a portion of the ball will extend through an opening 28 in each cupped portion 25. Between the cupped portions the holding plate 24 is secured directly against 80 the front plate 19 by rivets 29 as mentioned heretofore so that each cupped portion will be isolated from the other.

85 The sash 10 has the side sill or upright 30 thereof formed with a series of cupped portions 31, in the nature of indentations in the edge of the upright as shown and a strip or plate 32 conforming to the edge of the upright is secured by suitable screws 33 thereto, said plate 90 being formed with cupped portions 34 extending to the cupped portions 31 with the screw 33 passing into the upright between the adjacent cupped portions and opposite the points of riveting the holding 95 plate 24 to the front plate 19. It will now be seen that the cupped portions 25 of the holding plate, bulging out into the cupped portions 34 of the plate 32, in fact are in the nature of projecting contact surfaces or elements with one of the balls 27 in each one of the projecting contact elements adapted to have its periphery engage and bear against the plate 32 as shown so that the projecting portions of the upright between 100 adjacent projecting elements of the holding plate thus serving to hold the sash against rattling relative to the window frame, the springs 20 serving to exert sufficient pressure against the holding plate and its component parts, to provide the desired frictional contact between the structure secured 110

in the window frame and the plate 32 on the sash. It will now be apparent that when the sash shown in Fig. 1 is moved upwardly the resiliency of the springs 20 will permit 5 the holding plate and its parts to move backwardly into the window frame so that the plate 32 can ride over the anti-friction balls 27 and permit of the window being raised or lowered without great effort.

10 It will of course be understood that the described structure may extend any desired length along the edge of the sash and in the frame and that the springs 20 can be made of a desired strength to offer sufficient re- 15 sistance to prevent a heavy open sash from moving downward until a downward pull is exerted thereon.

By the provision of the anti-friction balls mentioned, I eliminate as far as possible, ex- 20 cessive friction which if present, would prevent the sashes from being raised or lowered except by undue effort and the anti-friction

balls furthermore permit of raising or low-
ering the sashes with very little noise.

Having described my invention, I claim— 25

The combination with a window frame having a slidingly mounted sash, of a sash holding device comprising a laterally mov-
able hollow member located between the side rail of the sash and the adjacent side of the 30 frame, a downwardly projecting wall in-
cluded in the hollow member for engagement in spaced sockets provided in the adjacent edge of the sash to hold the latter in ad-
justed position, an anti-friction ball project-
ing through an opening in the hollow mem-
ber for engagement with the socketed edge 35 of the sash to facilitate adjustment and anti-
friction balls located within the hollow mem-
ber and providing a bearing for the first 40
mentioned ball.

In testimony whereof I affix my signature.

JOHN W. JONES.
